US0D1058291S

(12) **United States Design Patent** (10) **Patent No.:** **US D1,058,291 S**
(45) **Date of Patent:** **** Jan. 21, 2025**

(54) **FROTHING IMPELLER**

(71) Applicant: **Dominic Symons**, Singapore (SG)

(72) Inventor: **Dominic Symons**, Singapore (SG)

(**) Term: **15 Years**

(21) Appl. No.: **29/962,992**

(22) Filed: **Sep. 13, 2024**

(51) **LOC (15) Cl.** **07-04**

(52) **U.S. Cl.**

USPC **D7/412; D7/377**

(57) **CLAIM**

The ornamental design for a frothing impeller as shown and described.

DESCRIPTION

FIG. 1 is a front left perspective view of a frothing impeller, shown in environmental use, showing my new design;

FIG. 2 is a front right perspective view thereof, shown in environmental use;

FIG. 3 is a bottom perspective view thereof, shown in environmental use;

FIG. 4 is a front elevation view thereof, with the rear elevation view being a mirror image, shown in environmental use;

FIG. 5 is a right side elevation view thereof, with the left side elevation view being a mirror image, shown in environmental use;

FIG. 6 is a bottom plan view thereof, shown in environmental use;

FIG. 7 is a front left perspective view thereof;

FIG. 8 is a front right perspective view thereof;

FIG. 9 is a bottom perspective view thereof;

FIG. 10 is a front elevation view thereof, with the rear elevation view being a mirror image thereof;

FIG. 11 is a right side elevation view thereof, with the left side view being a mirror image thereof;

FIG. 12 is a top plan view thereof; and,

FIG. 13 is a bottom plan view thereof.

The broken lines forming the base in the drawings illustrate environment only and forms no part of the claimed design.

1 Claim, 3 Drawing Sheets
